UNITED STATES PATENT OFFICE.

JOHN M. KELLY, OF MANITOWOC, WISCONSIN.

SAFETY GATE.

Application filed June 23, 1923. Serial No. 647,371.

To all whom it may concern:

Be it known that I, JOHN M. KELLY, a citizen of the United States, and resident of Manitowoc, in the county of Manitowoc and 5 State of Wisconsin, have invented certain new and useful Improvements in Safety Gates; and I do hereby declare that the following is a full, clear, and exact description thereof.

10 This invention relates to safety gates.

With safety gates as heretofore constructed, difficulty has been encountered in providing a gate which will actually stop vehicles without damaging the vehicle or the gate, and yet 15 provide a safety gate which will be light enough to be easily operated with a reasonable expenditure of power.

This invention is designed to overcome the above-noted defects, and objects of the invention are therefore to provide a flexible gate of strong and light construction, so formed that it will positively check vehicles which have been inadvertently driven into 25 the gate without damage to the gate or to the vehicle, and to provide such a type of gate so constructed that it may be operated with a minimum expenditure of power.

Further objects are to provide a gate which may be employed to temporarily close 30 streets along which electric cars normally pass, to provide simple means whereby the trolley wires may be temporarily severed, and to provide means for raising the gate when not in use above such trolley wires.

35 Further objects are to provide a gate in which the bracing of the parts is secured by the stationary portions of the gate, in which the movable portion is of extremely light weight, and in which a simple and effective 40 form of housing is provided for the gate when in elevated position.

An embodiment of the invention is shown in the accompanying drawings, in which—

45 Figure 1 is an elevation of the gate with parts in section and parts broken away to more clearly illustrate the construction.

Figure 2 is a transverse sectional view through one of the upright standards and the associated parts.

50 Figure 3 is a sectional view through the housing adjacent the motor.

Referring more particularly to the drawings, it will be seen that the gate comprises 55 a pair of tubular upright standards 1 and 2, adapted to be located upon opposite sides

of the roadway with their bases 3, firmly set in concrete. The upper ends of these uprights are joined by transverse beams 4, which firmly brace such upper portions and constitute with the uprights a rigid, rectangular structure. Sleeves 5 and 6 are slidably mounted upon the uprights 1 and 2, respectively, and loosely fit such uprights. These sleeves are provided with guiding rollers 7, which are journalled therein, engage the uprights and space the sleeves therefrom, constituting, in effect, friction reducing devices to facilitate the free sliding of the sleeves upon the uprights. These sleeves are provided with inwardly directed flanges 8, provided with apertures through which flexible steel cables 9 are threaded. These cables extend transversely across the roadway from one sleeve to the other sleeve and constitute a flexible barrier which, even when inadvertently struck by an automobile, will not damage either the gate structure or the automobile. If desired, an indicating signal, such as illustrated at 10 in Figure 1, may be clamped to certain of the strands in a position to be conspicuously displayed. In order to further brace the gate, a transverse angle iron 11 is secured to each of the sleeves, as, for instance, by means of brackets 12 and 13, formed upon the sleeves. This angle iron and the flexible cables 9 are elevated and lowered by simultaneously elevating or lowering the sleeves 5 and 6.

The means for elevating the sleeve may comprise a pair of cables 14 for each sleeve, secured to eyelets 15 formed upon opposite sides of the sleeves so as to prevent tilting or binding of the sleeves. These cables are operated by means of drums 16, over which they pass, such drums being rigidly secured to a pair of parallel shafts 17. These shafts are provided adjacent one end with duplicate gears 18, which, as indicated in Figure 2, are constantly in mesh and thereby secure simultaneous, uniform and reverse rotation of the shafts. The inner portions 19 of the cables are joined, or, in fact, the cables may be formed from a single piece of material, as indicated in Figure 2. These inner portions are attached to the upper end of the cylindrical counter-weights 20, mounted within the upright standards, each of the counter-weights being designed to roughly balance one half of the weight of the sliding or movable portions of the gate. The counter-

weights 20 may conveniently be mounted within the tubular uprights. In this manner they are concealed and protected, and a neat and attractive construction results.

5 Adjacent the upper end of one of the uprights, a supporting bracket 21 is secured and carries a relatively small electric motor 22. This motor is provided with a driving worm 23, which meshes with a worm wheel 24 rigidly secured upon one of the shafts 17, as indicated in Figures 1 and 3. In this manner, the shafts are power-driven and are held in locked position by the inherent characteristics of the worm drive.

10 15 In order to protect the gate mechanism against damage from rain and snow, a rectangular housing 25 is provided and is conveniently carried by means of the beams 4. This housing may be rounded adjacent its upper end, as indicated in Figure 2, and if desired may be similarly rounded adjacent its outer ends. It is provided with an offset portion 25' adapted to house the motor, as indicated in Figure 3. This housing may 20 carry any desired insignia or advertisement, and is preferably equipped with some form of signal, such as the bell 26, to give a further warning to the traffic.

15 It is intended that the gate shall be lifted 30 above the trolley wires, such as indicated at 27 in Figure 1. This is readily secured by attaching the trolley wire to suitable insulating supports 28, carried by opposite sides of the housing 25, and by providing a short 35 separate portion 27' for each of the trolley wires, as indicated in Figure 2. This detached portion in each instance is carried by insulating supports 28', secured to the angle iron 11, as indicated in Figures 1 and 2.

40 It will be seen from this construction that when the gate is lowered the movable portions 27 of the trolley wires are carried downwardly with the gate and are detached from the power circuit. However, when the 45 gate is in elevated position, the portions 27' are aligned with the portions 27 and the

continuity of the trolley wire is thus again established.

Obviously, any desired type of limit switch may be employed for limiting the 50 motion of the gate in either direction and any desired type of control may be employed for the motor, provided such control secures the necessary reversal of the motor for elevating and lowering the gate.

55 It will be seen that a safety gate has been provided which may be readily operated by power means, which will effectively stop vehicles without damage either to the vehicle or to the gate, and which is of attractive design and of extremely simple and sturdy construction.

60 I claim:

1. A safety gate comprising a pair of spaced, tubular uprights, a pair of elongated 65 sleeves slidably carried by said uprights, a plurality of flexible barriers stretched between said sleeves, counterweights located within said tubular uprights, a cable for each end of said gate connecting the appropriate sleeve with the corresponding counterweight, and an electric motor operatively connected to said cables.

2. A safety gate comprising a pair of tubular uprights, a pair of elongated 70 sleeves slidably mounted upon said uprights, a plurality of flexible barriers connecting said sleeves, a counter-weight in each upright, a pair of cables extending from each counterweight to opposite sides of the corresponding sleeve, a pair of drums for each pair of cables, each of said drums having a gear meshing with the gear of the corresponding drum of the pair, a shaft connecting a drum of one pair with a drum of the 75 other pair, and an electric motor for driving said drums.

80 In testimony that I claim the foregoing I have hereunto set my hand at Manitowoc, in the county of Manitowoc, and State of Wisconsin.

JOHN M. KELLY.
